US00D621900S

(12) **United States Design Patent**
Cink et al.

(10) **Patent No.:** **US D621,900 S**
(45) **Date of Patent:** ** *Aug. 17, 2010

(54) **RODENT MANAGEMENT SYSTEM**

(75) Inventors: **James H. Cink**, Ballwin, MO (US);
Jonathan D. Berger, St. Louis, MO (US); **Brian James Mann**, Wildwood, MO (US); **Edward Francis Marshall**, Lansing, MO (US); **Henry Wayne Moran**, Ballwin, MO (US); **James David Poling**, Clarkson Valley, MO (US)

(57) **CLAIM**

The ornamental design for a rodent management system, as shown and described.

DESCRIPTION

FIG. 1 is a front perspective of a rodent management system according to our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom plan view thereof; and,

FIG. 7 is a rear elevational view thereof.
